No. 867,196.

PATENTED SEPT. 24, 1907.

W. L. GILBERT.

LEASE ROD SUPPORTING DEVICE.

APPLICATION FILED SEPT. 10, 1906.

UNITED STATES PATENT OFFICE.

WILLIAM L. GILBERT, OF AUBURN, MAINE, ASSIGNOR, BY DIRECT AND MESNE ASSIGNMENTS, TO GILBERT LEASE ROD SUPPORTER COMPANY, A CORPORATION OF MAINE.

LEASE-ROD-SUPPORTING DEVICE.

No. 867,196.

Specification of Letters Patent.

Patented Sept. 24, 1907.

Application filed September 10, 1906. Serial No. 334,007.

To all whom it may concern:

Be it known that I, WILLIAM L. GILBERT, a citizen of the United States, residing at Auburn, in the county of Androscoggin and State of Maine, have invented certain 5 new and useful Improvements in Lease-Rod-Supporting Devices, of which the following is a specification.

My present invention relates to improvements in looms and more especially to an improved device or attachment for supporting lease rods.

10 The object of the invention is to provide a device or apparatus by which the lease rods will be supported in such manner as to be capable of a certain rising and falling, and a rocking movement by which any threads or yarns of the warp which have adhered to each other 15 may be automatically separated.

A further object is to provide a device or apparatus by which the uneven tension on the warp, caused by the upward and downward movement of the harness, will be prevented.

20 A further object is to construct and mount the attachment in such a manner that, in case the threads or yarns of the warp have become so securely attached to or entangled with each other as to be incapable of automatic separation without breaking, the loom will be automatically stopped.

25 A further object is to provide an attachment to produce these results which shall be simple, durable and efficient in operation and which may be manufactured at a minimum cost and be easily applied to any existing 30 loom.

The invention is illustrated in the accompanying drawing in which—

Figure 1 is a side elevation of a sufficient portion of a loom to illustrate the application of my invention. 35 Fig. 2 is a plan view of one of the attachments showing a portion of the lease rods, and Fig. 3 is a section on line 3—3 of Fig. 2. Fig. 4 is a view of the opposite end attachment with an indicator attached.

40 Referring by reference characters to this drawing, the numeral 4 designates the frame of the loom, 5 the harness, 6 the warp threads, and 7 the rock lever of the ordinary stop motion mechanism. These parts may be of the ordinary or any desired construction and are too well known to necessitate any further description.

45 In this drawing, I have for convenience shown the attachment only at one end of the loom, but it will be understood that there is an attachment at each end by which the lease rods are supported but as they are practically duplicates of each other, the illustration and description of one end of the loom only is thought to be 50 amply sufficient. Each of the attachments comprises a bracket or standard 8 which has a forked or slotted lower end by which it may be adjustably bolted to the frame of the loom. The upper end of this standard

is hollow to provide a socket within which is located 55 the shank 9 of a member 10. The shank 9 is of smaller diameter than the bore of the socket and is encircled by a spring 11 which bears against the enlarged upper portion of the member 10 and tends to hold it elevated for a certain distance above the bracket. A cross or 60 rocking member 13 has a slotted portion 14 pivotally mounted upon the head 12 of the member 10 by means of a pivot pin, the amount of the rocking motion being limited by stops or projections 15. This cross member 13 supports at one side a slide 15 which carries one 65 of the lease rods 16, as shown. The slide 15 may conveniently have a tongue and groove engagement with the member 13 and its movement may be limited by a set screw 16 passing through a slot in the slide and engaging the member 13. Upon the opposite side of the 70 pivot, the member 13 carries a vertical lug 13^a through an opening in which passes a rod 17 to which is secured a block 18 which carries the end of the other lease rod 19. The rod 17 is encircled by a helical spring 20 which bears at one end against the lug 13^a and at the 75 other end against the slide 15 and tends to keep the slide 15 and block 18 which is, of course, connected rigidly thereto through rod 17, pressed constantly towards the left or in the direction opposite to the feed of the warp threads. 80

I may conveniently secure to the under side of the block 18 at one end of the loom an arm 21 to which is connected a notched slide bar 22 which passes through a guide 23 on the frame of the loom and has its end normally supporting a drop bar 24, as shown in Fig. 1, the 85 bar 22 being so arranged that if moved to the right its notched portion 22^a will allow it to descend and lower the drop bar 24 to engage the stop motion mechanism indicated at 7.

From the foregoing description it is thought the operation of my improved attachment will be obvious, but may be briefly stated as follows: The movement of the warp threads under the action of the harness will cause the member 13 which supports the lease rods to have a vertical movement imparted thereto. Thus 90 the lease rods will have a limited up-and-down movement corresponding with the movement of the harness. The movement of the harness and warp threads will also cause the member 13 to rock on its pivot, thus alternately raising and lowering the lease rods and this 100 will tend, should any of the warp threads adhere to each other, to work them apart, and this without any danger of the breakage of the threads. Should, however, any of the threads or yarns of the warp be so firmly stuck together or entangled as to prevent their 105 automatic separation without breaking, the slide 15 and the lease rods will be moved to the right against the tension of the spring 20, thereby moving the bar 22

to the right until its notched portion drops down and lowers the drop bar 24 and operates the stop motion mechanism to arrest the loom.

I may if desired provide the attachment which supports the lease rods at the opposite end with an indicator, which, whether or not the stop motion connections are used, or if used fail to work, will show to the attendant that the threads are entangled beyond automatic separation. Such a device is shown in Fig. 4 10 and comprises an arm 25 pivoted to the member 13 and designed to normally drop down out of indicating position, being held in such position by gravity. The arm has an indicator head or disk 26 of any suitable shape, and an extension 27 designed to rest against the face of 15 member 18. When this member is moved suddenly by the entangled warp threads its contact with the extension will throw the arm up into signaling position.

The extension is made of spring material so as to ride over the face and drop behind the lower edge of the 20 member 13, holding the indicator elevated.

Having described my invention, what I claim is:

1. In combination in a loom, lease rod carrying members supported on the loom frame and lease rods carried by said members said lease rods being horizontally movable with 25 relation to said members with the movement of the warp threads.
2. In combination in a loom, lease rod carrying members supported on the loom frame and having vertical movement thereon, and lease rods carried by said members and having 30 horizontal movement thereon caused by the warp threads.
3. In combination in a loom, lease rod carrying members supported on the loom frame and having vertical spring movement thereon, and lease rods carried by said members, having horizontal spring controlled movement on said 35 members.
4. In combination in a loom, lease rod carrying members

supported on the frame of the loom and having vertical spring controlled movement thereon and a lease rod supported upon said members, having horizontal movement on said members.

40

5. In combination in a loom, a lease rod, and lease rod carrying members supported upon the loom frame having vertical spring movement on said frame and springs arranged to control the horizontal movement of the lease rod.

45

6. In combination in a loom, lease rod carrying members having vertical spring movement on their supports, and having also rocking movement in vertical planes, and lease rods carried on said members having spring controlled horizontal movement on said members.

50

7. In combination in a loom, lease rod carrying members, horizontally movable lease rods carried on said members, springs normally pressing said lease rods in a direction opposite to that of the feed of the warp threads, stop mechanism for the loom and means connected with the lease rods for controlling the stop motion, substantially as described.

55

8. A lease rod carrying attachments for looms, comprising members which directly support the lease rods, or rod, said member being adapted to move vertically on said supports upon interposed springs, means for permitting horizontal movement of the lease rod upon said supports and springs for normally pressing the lease rod in a direction opposite that of the feed of the warp threads, substantially as described.

60

9. In combination in a loom a lease rod carrying member composed of two parts, one movable on the other and directly carrying the lease rod or rods, a spring arranged to control the movable part a stop motion mechanism for the loom, and an arm connected to the movable part arranged with mechanism to engage the stop motion mechanism by movement of said movable part.

65

In testimony whereof, I affix my signature in presence of two witnesses.

WILLIAM L. GILBERT.
